UNITED STATES PATENT OFFICE.

VINCENT E. HEYWOOD, OF WORCESTER, MASSACHUSETTS.

PROCESS OF MAKING WINDOW-ENVELOPS.

1,353,588.

Specification of Letters Patent. Patented Sept. 21, 1920.

Application filed May 23, 1919. Serial No. 299,255.

To all whom it may concern:

Be it known that I, VINCENT E. HEYWOOD, a citizen of the United States, residing at Worcester, in the county of Worcester and 5 State of Massachusetts, have invented certain new and useful Improvements in Processes of Making Window-Envelops, of which the following is a specification.

My invention relates to a solid face, or 10 one-piece window envelop, of the type shown in U. S. Letters Patent, No. 835,850, in which there is a transparent part on the address, or front side of the envelop, produced by applying varnish, or other material upon the envelop blank.

My invention particularly relates to an improved method of making window envelops of the type above referred to, and my invention consists in my improved method 20 of making said envelops.

In the ordinary method of making window envelops of the type above referred to, the varnish, or other material, when applied to the envelop blank, to make the transparent part therein, leaves this part of the envelop blank in a sticky condition, so that it is necessary to dry this part before the envelop blank can be folded.

In my improved method of making a window envelop of the type referred to, I apply 30 immediately after the gum for the flaps, and the varnish for the transparent part have been applied to the blank, a separate transparent piece of paper on the inner side of 35 the blank over the sticky varnished part, to cover said varnished part and allow the envelop blank to pass immediately to the folding mechanism to be folded, without waiting for the varnish to dry.

40 Referring to the drawing:

Figure 1 shows a front view of a window envelop embodying my invention, and made according to my improved method.

Fig. 2 shows an envelop blank before any 45 operation has been performed thereon.

Fig. 3 shows the envelop blank shown in Fig. 2, after the gum has been applied to the top, and bottom flaps, and the varnish, or other material has been applied to the body 50 portion of the blank, to make the transparent part or window, and

Fig. 4 shows the blank shown in Fig. 3, after the transparent piece of paper has been applied to the varnished part.

55 In the accompanying drawing, 1 is the blank from which the envelop is made, which

blank may be of any desired shape or configuration. 2, and 3 are the side or end flaps, 4, and 5 are the top and bottom flaps, to which gum 6 is applied in any ordinary 60 way, and on any well known machine for making window envelops. 7 is the transparent part or window, which in this instance is of the usual oblong shape, and is made by applying varnish, or other suitable 65 material upon the inner side of the blank 1. The varnish is preferably applied to the blank 1, at the same time that the gum 6 is applied. The gum, and varnish may be applied to the inside of the envelop blank, at 70 the picker mechanism of the machine.

The piece of paper 8, preferably of transparent material, Fig. 4, is placed on the inside of the blank to extend over the varnished surface 7. The placing of the piece 75 of paper 8 over the varnished surface 7, and the folding of the blank, may be performed at the plunger mechanism of the envelop machine.

The folding of the blank produces the 80 complete solid face envelop 9, having the transparent window 7, shown in Fig. 1.

The placing of the piece of paper 8, on the varnished surface 7, immediately after the varnish has been applied to the blank, 85 forms a covering for the varnish, and overcomes the necessity of drying the varnished surface prior to the folding of the blank, and prevents the flaps from sticking to the varnished surface.

90 My improved method of making a solid face window envelop may be carried out on any well known type of machine for making window envelops.

It will be understood that my improved 95 method of making window envelops of the type above referred to, may be varied somewhat.

The gum for the flap, and the varnish for the transparent part, are preferably applied 100 to the envelop blank at the same time, and at one operation. The piece of transparent paper 8 is preferably applied to the varnished surface, and the blank folded, to form the complete envelop, at the same time, 105 and at one operation.

Having thus described my invention, what I claim as new and desire to secure by Letters Patent is:—

110 1. The improved method of making an envelop having a transparent part or window formed by applying varnish or other

material upon the inner side of the envelop blank, which consists in the application of a piece of transparent paper upon the inside of the envelop blank, to extend over and cover the transparent part in the blank.

2. The improved method of making a window envelop, which consists in applying upon the inside of the envelop blank gum upon the flaps, and varnish or other material 10 to form the transparent part or window, and then applying a piece of transparent paper on the inner side of the blank, to extend over and cover the varnish or other material, and then folding the blank to form the complete 15 envelop.

3. The improved method of making a window envelop, which consists in applying

gum upon the flaps, and varnish or other material to form the transparent part or window, at one operation, and then applying 20 a piece of transparent paper over the varnish or other material, and folding the blank at a second operation to form the complete envelop.

4. An improved window envelop having a 25 transparent surface formed by varnish or other material applied to the inside of the envelop blank, and a transparent piece of paper applied to the inner side of the blank, and covering the transparent part.

VINCENT E. HEYWOOD.
